PORTABLE CROP HEATER

William R. Fowler, Jr., Selma, Calif.

Application October 19, 1950, Serial No. 191,058

9 Claims. (Cl. 47-2)

1

This invention relates to a portable orchard heater.

An object of my invention is to provide a traveling crop heater, which provides greater flexibility of operation to predetermine the outlet temperature of the air blown from the heater and to control a primary and secondary air supply in addition to the products of combustion.

Features of my invention include: a combustion chamber surrounded by a flow of primary air supply to cool the walls of the chamber; a diffuser adjusted to determine the optimum diffusing of the products of combustion into the primary air flow and thus determine the outlet temperature of the heated air; a secondary air supply introduced into the air flowing from said diffuser and drawn in at a rate of flow determined by said diffuser; and a suction and blower device to further mix said air flow and to blow the heated air into the atmosphere generally laterally and at points below the axis of the heater.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a side view of my heater.

Fig. 2 is a sectional view of my heater, the section being taken on the lines 2-2 of Fig. 1.

Fig. 3 is a partly sectional side view of my heater.

Fig. 4 is a rear view of my heater.

In the illustrative embodiment of my invention a generally cylindrical housing 1 is suitably mounted on a wheeled carriage frame 2 which latter is adapted to be hooked to a tractor or truck or the like. The housing 1 has a generally frusto-conical intake end 3 and a similar exhaust end 4, which have respectively central openings 6 and 7.

A generally cylindrical combustion chamber 8 is supported concentrically within the housing 1

2

on radial spacing brackets 5 so that an air passage 10 surrounds the entire exterior of the combustion chamber 8. The end of the combustion chamber 8 adjacent the intake end 4 of the housing 1 is closed by an end wall 9 on which is mounted a suitable burner 11. Fuel lines 12 conduct fuel to the burner 11 from fuel containers 13 mounted on the top of the housing 1. The other end 14 of the combustion chamber 8 is open and is spaced inwardly from the exhaust opening 7 of said housing 1. The open end 14 of the combustion chamber 8 is smaller than the diameter of said exhaust opening 7.

On the intake end wall 9 of the combustion chamber 8 are intake ports 16 the openings of which are regulated by a suitable adjustable valve plate 17, which regulate the air intake into the combustion chamber 8.

A diffuser 18 is provided within the exhaust end 4 of the housing 1. The diffuser 18, in the present illustration, is conical. The apex 19 of the conical diffuser 18 points toward and is spaced from the open end 14 of the combustion chamber 8. The base 21 of the diffuser 18 faces toward and is spaced inwardly from the exhaust opening 7 of the housing 1. The sides of the conical diffuser 18 diverge oppositely to the converging sides of the exhaust end 4 of the housing 1. Thus the conical diffuser is positioned between the open end 14 of the combustion chamber 8 and exhaust opening 7 of the housing 1, and it is in axial alignment with the combustion chamber 8. The general function of the diffuser 18 is to deflect the products of combustion issuing from the combustion chamber 8 generally outwardly for intermixing said products of combustion with the air flow through the housing 1, and to determine the size of the passage of the mixture through the exhaust end 4 of the housing 1. This in turn determines the velocity of flow through said outlet end 4 and correspondingly determines the temperature of a given mixture in said flow.

For the purpose of constricting or expanding the passage between the diffuser base 21 and the exhaust end 4 of the housing 1, the position of the diffuser 18 is adjustable axially or longitudinally relatively to the exhaust end 4 of the housing 1. In the present illustration, four supporting spokes 22 extend from the diffuser 18. The outer ends of the spokes 22 are longitudinally slidable in longitudinal channel brackets 23 on the outside of the exhaust end 4 of the housing 1. Each spoke 22 has an offset head 24 thereon outside of its channel 23. A bolt 26 extending through said offset head 24 is tightened against

the channel 23 to fasten the spoke 22 in adjusted position. The spokes 22 slidably extend through slots 25 in the walls of said exhaust end 4. The diffuser 18 is thus shifted to the desired spacing and then the bolts 26 are tightened to hold it in said adjusted position.

At the exhaust end 4 of the housing 1 is formed a secondary air chamber 27 which has circumferential secondary air intake ports 28 adjacent and around the exhaust end 4. In a plenum chamber 29 communicating with said secondary air chamber 27 is a fan 31. The shaft 32 of said fan 31 is journaled in bearings 33 supported on suitable spokes 34 on the wall of said chambers 27 and 29. A suitable transmission 36 transmits rotation to said fan shaft 32 from an engine or motor 37 mounted on the top of the housing 1.

The plenum chamber 29 extends rearwardly and downwardly and terminates in lateral discharge conduits 38 generally below the level of the axis of the housing, so as to discharge the heated air to opposite sides from the lower portion of the unit.

In operation the fan 31 draws air through the housing 1. A regulated amount of air is drawn into the combustion chamber 8. The primary air flow cools the walls of the combustion chamber 8 and absorbs certain of the radiating heat therefrom. The products of combustion issuing from the combustion chamber 8 are directed outwardly by the diffuser 18 and are intimately intermixed with the primary air flow at the housing outlet 4 so as to assure complete combustion and heat interchange. The velocity of outflow past the diffuser 18 coacts with the suction of the fan 31 to draw in the secondary air supply through the intake ports 28 and the heated mixture enters the plenum chamber 29 from which it is blown out through the lateral discharge conduits 38. As the unit is carried on the carriage 2 through an orchard or the like, a desired volume of suitably heated air is thus discharged at a comparatively low level and as it spreads and rises it raises the temperature of the atmosphere without injury to the crop. The complete, predetermined intermixture obviates soot and smoke yet efficiently conditions the atmosphere as desired.

I claim:

1. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a secondary air chamber at said outlet having inlet ports for drawing in a secondary air supply, a diffuser device at said outlet to intermix said products of combustion and the air flow from said primary air passage, generally lateral discharge conduits leading from said secondary air chamber for discharging heated air into the atmosphere, and an air circulating device to draw air through said primary passage and through said secondary air chamber and to force the mixture out through said lateral discharge conduits.

2. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a

secondary air chamber at said outlet having inlet ports for drawing in a secondary air supply, a diffuser device at said outlet to intermix said products of combustion and the air flow from said primary air passage, generally lateral discharge conduits leading from said secondary air chamber for discharging heated air into the atmosphere, and an air circulating device to draw air through said primary passage and through said secondary air chamber and to force the mixture out through said lateral discharge conduits, said diffuser device being aligned with said combustion chamber and directing the products of combustion generally outwardly toward the periphery of said outlet.

3. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a secondary air chamber at said outlet having inlet ports for drawing in a secondary air supply, a diffuser device at said outlet to intermix said products of combustion and the air flow from said primary air passage, generally lateral discharge conduits leading from said secondary air chamber for discharging heated air into the atmosphere, and an air circulating device to draw air through said primary passage and through said secondary air chamber and to force the mixture out through said lateral discharge conduits, said diffuser device being aligned with said combustion chamber and directing the products of combustion generally outwardly toward the periphery of said outlet, and means to adjust the distance axially between said diffuser device and said secondary air chamber.

4. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a secondary air chamber at said outlet having inlet ports for drawing in a secondary air supply, a diffuser device at said outlet to intermix said products of combustion and the air flow from said primary air passage, generally lateral discharge conduits leading from said secondary air chamber for discharging heated air into the atmosphere, and an air circulating device to draw air through said primary passage and through said secondary air chamber and to force the mixture out through said lateral discharge conduits, said combustion chamber discharging toward said diffuser device, and the walls of said diffuser device diverging outwardly away from said combustion chamber.

5. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a secondary air chamber at said outlet having inlet ports for drawing in a secondary air supply, a diffuser device at said outlet to intermix said products of combustion and the air flow from said

primary air passage, generally lateral discharge conduits leading from said secondary air chamber for discharging heated air into the atmosphere, and a blower device in said secondary air chamber for drawing air through said primary air passage and through said secondary air chamber and blowing the mixture out through said lateral discharge conduits.

6. In a portable crop heater of the character described, a housing, a portable carriage supporting said housing, an air inlet at the forward end of the housing, an outlet at the rear end of the housing, a combustion chamber within said housing between said inlet and said outlet being spaced from said housing to form a primary air passage all around said combustion chamber, a secondary air chamber at said outlet having inlet ports for drawing in a secondary air supply, a diffuser device at said outlet to intermix said products of combustion and the air flow from said primary air passage, generally lateral discharge conduits leading from said secondary air chamber for discharging heated air into the atmosphere, and an air circulating device to draw air through said primary passage and through said secondary air chamber and to force the mixture out through said lateral discharge conduits, said diffuser device including a substantially conical element axially aligned with said combustion chamber and positioned with its apex pointing toward said combustion chamber.

7. In a portable crop heater of the character described, a housing, a portable carriage for carrying said housing, an inlet and an outlet on said housing, a combustion chamber in said housing spaced from the walls of said housing and discharging products of combustion toward said outlet, a secondary air chamber at said outlet having secondary air inlets, lateral discharge conduits leading from said secondary air chamber to opposite sides of the lower portion of said secondary air chamber, a blower in said secondary air chamber for drawing air through said housing and said chamber and to blow the mixed air out through said discharge conduits, and a diffuser element between said blower and said combustion chamber to direct the products of combustion and the air from said housing generally outwardly and toward said secondary air chamber.

8. In a portable crop heater of the character described, a housing, a portable carriage for carrying said housing, an inlet and an outlet on said housing, a combustion chamber in said housing spaced from the walls of said housing and discharging products of combustion toward said

outlet, a secondary air chamber at said outlet having secondary air inlets, lateral discharge conduits leading from said secondary air chamber to opposite sides of the lower portion of said secondary air chamber, a blower in said secondary air chamber for drawing air through said housing and said chamber and to blow the mixed air out through said discharge conduits, and a diffuser element between said blower and said combustion chamber to direct the products of combustion and the air from said housing generally outwardly and toward said secondary air chamber, generally inwardly inclined walls constricting said outlet relatively to said housing, said diffusing device having outwardly inclined walls to deflect the products of combustion toward said outlet walls for intermixture with the air flow through said housing.

9. In a portable crop heater of the character described, a housing, a portable carriage for carrying said housing, an inlet and an outlet on said housing, a combustion chamber in said housing spaced from the walls of said housing and discharging products of combustion toward said outlet, a secondary air chamber at said outlet having secondary air inlets, lateral discharge conduits leading from said secondary air chamber to opposite sides of the lower portion of said secondary air chamber, a blower in said secondary air chamber for drawing air through said housing and said chamber and to blow the mixed air out through said discharge conduits, and a diffuser element between said blower and said combustion chamber to direct the products of combustion and the air from said housing generally outwardly and toward said secondary air chamber, generally inwardly inclined walls constricting said outlet relatively to said housing, said diffusing device having outwardly inclined walls to deflect the products of combustion toward said outlet walls for intermixture with the air flow through said housing, adjustable air ports on said combustion chamber, and adjustable means connected to said diffuser element for setting the position of said diffuser element to a selected position in said outlet to determine the velocity of air flow through said outlet.
